Primary Examiner — Marissa J Cash*Assistant Examiner* — Altaira J Swangin(74) *Attorney, Agent, or Firm* — Zagorin Cave LLP;
Robert W. Holland(57) **CLAIM**

The ornamental design for an information handling system, as shown and described.

DESCRIPTION

FIG. 1 is a front perspective view of the information handling system showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 is a front perspective environmental view of the information handling system of FIGS. 1-8 shown in an open position.

Broken lines immediately adjacent shaded and claimed surfaces, represent boundaries of the claim and form no part thereof; all other broken lines shown in the drawings illustrate portions of the information handling system, and form no part of the claimed design.

1 Claim, 6 Drawing Sheets(56)
